Inventor

S. O. Bumgarner.

Attorney

A. Randolph, Jr.

UNITED STATES PATENT OFFICE.

STEPHEN O. BUMGARNER, OF WAVERLY, OHIO.

GATE.

Application filed April 1, 1924. Serial No. 703,559.

To all whom it may concern:

Be it known that I, STEPHEN O. BUMGARNER, a citizen of the United States, residing at Waverly, in the county of Pike and State of Ohio, have invented certain new and useful Improvements in Gates; and I do hereby declare the following to be a full, clear, and exact description of the invention, such as will enable others skilled in the art to which it appertains to make and use the same.

The invention relates to gates for controlling an opening in an enclosure and has for its object to provide a gate which will operate in a comparatively small space and which may be opened and closed from either approach and which will not tend to sag, since it is mounted to swing in a vertical plane about a horizontal pivot, said gate being counterbalanced by means of springs which also operate to ease the movement of the gate when reaching the limit of its movement in either direction, as when opening or closing.

The invention relates more particularly to the mountings and operating mechanism, the parts being adjustable and the gate operating means also serving to actuate the latch, whereby the gate is released preliminary to moving the same into open position.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is a side view of a gate and adjunctive parts embodying the invention;

Figure 2 is a view similar to Figure 1 showing the gate in open position;

Figure 3 is a top plan view, an intermediate portion of the gate being broken away;

Figure 4 is a sectional view on the line 4-4 of Figure 1, looking to the left as designated by the arrows;

Figure 5 is an enlarged sectional view on the line 5-5 of Figure 1;

Figure 6 is an enlarged sectional view on the line 6-6 of Figure 1, and

Figure 7 is a sectional view on the line 7-7 of Figure 1.

Corresponding and like parts are referred to in the following description and designated in the several views of the drawings by like reference characters.

The numeral 10 represents the gate which may be of any preferred construction and which is pivotally mounted at one corner, as indicated at 11, to swing in a vertical plane by a jumping action. The numeral 12 designates the latch post at one side of the gate opening and 13 designates a pair of posts at the opposite side of the gate opening and spaced apart to admit of the gate operating therebetween. A latch 14 is provided at the outer or swinging end of the gate and is adapted to engage an opening 15 in the post 12, whereby to hold the gate in closed position. A helical spring 16 is mounted upon the latch 14 and one end is connected to the upright at the swinging end of the gate and the other end engages the latch 14. The spring 16 normally holds the latch 14 projected and in position to engage the opening 15. A flexible connection 17 is attached at one end to the latch 14 and its other end is connected to a ring 18 to which other flexible connections 19, 19^a and 20 are connected.

The gate hinge or mounting is of bracket formation and comprises an upright member 21 and a horizontal member 22, the junction of these members consisting of a sleeve 90 which receives the pivot 11. The upright member 21 is clipped or otherwise secured to the upright at the inner or pivot end of the gate. The horizontal member 22 is clipped or otherwise secured to the lowest element of the gate and is of a width to project beyond opposite sides of the gate, the projecting portions having longitudinal slots 23 formed therein which receive the fastenings by means of which a crossbar 24 is adjustably connected to the part 22. Said crossbar 24 terminates in hooks to which the lower ends of helical springs 25 are connected, the upper ends of said springs being attached to plates 26 which are adjustably connected to the posts 13. In this manner, the tension of the springs 25 may be regulated and the relative position of the same adjusted. The springs 25 are normally under tension and operate as counterbalancing means for the gate and also as shock-absorbing means to ease the move-

ment of the gate when swinging in either direction.

Cap plates 27 surmount each of the posts 13 and support guide pulleys 28 over which 5 operating cords 19 pass, said cords extending along opposite sides of the gate and being attached to the ring 18. A pair of guide pulleys 29 is provided near the top of each of the posts 13 and just beneath the cap 10 plates 27 and the cords 19 pass therebetween, as shown most clearly in Figure 1. The operating cords 19 pass through openings formed in the cap plates 27. A crossbar 30 is attached to the outer end of the member 15 22 and projects beyond opposite sides of the gate and operates to engage the springs 25 when the gate is in open position, as indicated most clearly in Figure 2. A stop 31 is attached to the lowest element of the gate 20 and engages the post 13 to limit the movement of the gate when swung into open position.

The operating cords 19 or like parts extend from opposite sides of the gate to any 25 predetermined point and are adapted to be pulled upon either to open or to close the gate, the movement of the gate being assisted by means of the springs 25. When approaching the gate and pulling upon the 30 operating end of the cord 19 or like part, the latch 14 is operated, thereby releasing the gate, and a continued pull upon the cord

19 moves the gate through cord 20 into open position shown in Figure 2, by a jumping action. After the person has passed through the gate opening, the gate is closed by pulling upon the other connection 19 which through cord 19 moves the gate from the position shown in Figure 2 to that indicated in Figure 1, the gate being held closed by the latch 14 engaging the opening 15.

What is claimed is:

1. In combination, a gate post, a gate pivoted thereto to swing in a vertical plane about a horizontal axis, a bracket mount for 45 the gate having a side extension in which is formed a longitudinal slot, and a helical spring between said post and slotted portion of the mount and having adjustable connection with the slot of the latter.

2. In combination, a gate post, a jump gate, a mount for the latter having a lateral extension in which is formed a longitudinal slot, a plate having adjustable connection with the post and a helical spring connected 55 at one end to said plate and having adjustable connection with the slotted portion of the gate mount.

In testimony whereof I affix my signature in presence of two witnesses.

STEPHEN O. BUMGARNER.

Witnesses:

PERU HUFF,
T. A. BAVUR.
